ARTHUR H. ROGERS AND JAMES H. ROGERS, OF SPRINGFIELD, MASS.

PRINTING-STAMP.

SPECIFICATION forming part of Letters Patent No. 341,771, dated May 11, 1886.

Application filed January 4, 1886. Serial No. 187,511. (No model.)

To all whom it may concern:

Be it known that we, ARTHUR H. ROGERS and JAMES H. ROGERS, citizens of the United States, residing at Springfield, in the county of 5 Hampden and State of Massachusetts, have jointly invented new and useful Improvements in Self-Inking Printing-Stamp, of which the following is a specification.

This invention relates to improvements in 10 self-inking hand-stamps, the object being to provide, in combination with a table having an inking-pad thereon and with a die-block, improved means for moving said die-block from said inking-pad to another part of the table, 15 on which is laid paper to be printed, and vice versa, and improved devices for maintaining the die-block in proper position during said movements thereof.

In the drawings forming part of this specification, is illustrated in Figure 1, in perspective view, a self-inking hand-stamp embodying our invention. Fig. 2 illustrates a partial longitudinal section of a construction held to be the equivalent of Fig. 1.

25 In the drawings, A is the table of the machine, made of suitable cast metal or other suitable material, and adapted, if desired, to be secured on a desk or other place for use. Two arms, b b, are attached to the table A on 30 opposite sides thereof, which project above its surface, as shown, and at one end of said table are two upwardly projecting roller-bearings, c, between which is hung a roller, d, the ends of the latter entering suitable perforations in 35 said bearings, said roller being permitted to have a free rocking motion therein. A guiding-arm, o, for the die-block, has one end engaging in a transverse perforation in the roller d, and the free end of said arm reaches over 40 the table A between said arms b. A guiding or registering strip, e, is attached to the table just forward of the arms b, which serves to bring an envelope, piece of paper, or other thing on which the die-block is to print into 45 proper position under the latter. A yoke, h, consisting of a handle-piece, i, uniting the upper ends of two arms and the latter, has the lower ends of its said arms pivoted to the ends of said arms b on the table A, said yoke being 50 capable of being swung from the position in which it is shown in the drawings to one which will bring its end in about the same relation

to the opposite end of table A, its intermediate position while swinging being shown by the dotted lines in the drawings.

55 The die-block K may be of wood or metal, having an ordinary rubber stamp with letters and figures thereon, secured to its under face, or its printing characters may be of ordinary type suitably secured therein. Said die-block 60 is pivotally attached to the arms of said yoke h and between the said arms, as shown, and the above-mentioned guiding-arm o passes through a perforation in said die-block in the plane of the face of the latter, the die-block being free 65 to slide on said arm; or the latter may be attached to said block and slide in the roller d, as shown in Fig. 2. An inking-pad, m, of the well-known description, is secured on the table A, said pad being shown under the die-block in the drawings, and said block being 70 thereshown as it is when being pressed against said pad to be inked.

75 The operation of the above-described improvements is as follows: The paper or other thing to be printed is laid on the table A, with its rear edge against the registering-strip e. The handle-piece i of the yoke h is then seized and pressed downward more or less to force the face of the die-block against the pad m to 80 ink the stamp, and then the end of said yoke is swung up and over, as shown by said dotted lines, toward the opposite end of table A, thereby lifting block K off from the pad m, and carrying it over the table and bringing it down 85 upon the aforesaid paper to be printed upon, that portion of the yoke h extending beyond the die-block serving as a lever to give force to the impression of said block. The guiding-arm o, on which the die-block slides when 90 swung from the inking-pad onto the table or from the latter back onto the inking-pad to ink the stamp, serves to keep the face of the latter in a proper plane when it is brought down for inking or printing, and prevent said 95 block from swinging between the arms of the yoke.

The stamp could be manipulated successfully for printing without the intervention of the guiding-arm o, if desired, as the operator can, 100 while swinging yoke h, extend a finger onto the top of the die-block, and thus insure its proper position with some degree of accuracy when it strikes the inking-pad or paper; but

the machine can be much more rapidly and effectively worked when constructed as shown in the drawings.

What we claim as our invention is—

- 5 1. A self-inking printing-stamp consisting of the table A, on which to lay the thing to be printed, the inking-pad m, attached to said table, the yoke h, pivoted on opposite sides of the latter, the die block K, adapted to have printing characters attached thereto, pivoted between the arms of said yoke, and the guiding-arm o, pivotally connected to said table and passing loosely through said die-block in the plane of its face, combined and operating 25 substantially as set forth.
- 10 15 2. A self-inking printing-stamp consisting

of the table A, on which to lay the thing to be printed, the inking-pad m, attached to said table, the yoke h, pivoted on opposite sides of the latter, the die block K, adapted to have 20 printing characters attached thereto, pivoted between the arms of said yoke, and the guiding-arm o, pivotally connected to said table and passing loosely through said die-block in the plane of its face, combined and operating 25 substantially as set forth.
